TURNSTILE.

APPLICATION FILED DEC. 26, 1918.

1,339,076.

Patented May 4, 1920.

UNITED STATES PATENT OFFICE.

CONRAD D. TRUBENBACH, OF MOUNT VERNON, AND DIEDRICH BALDWIN SANNEMAN, OF BROOKLYN, NEW YORK, ASSIGNEES TO PEREY MANUFACTURING COMPANY, INC., A CORPORATION OF NEW YORK.

TURNSTILE.

1,339,076.

Specification of Letters Patent.

Patented May 4, 1920.

Application filed December 26, 1918. Serial No. 268,975.

To all whom it may concern:

Be it known that we, CONRAD D. TRUBENBACH and DIEDRICH B. SANNEMAN, citizens of the United States, and residents, respectively, of Mount Vernon, in the county of Westchester and State of New York, and of the borough of Brooklyn, in the county and State of New York, have invented new and useful Improvements in Turnstiles, of which 10 the following is a specification.

This invention relates to turnstiles, and particularly to turnstiles to be used in railway cars.

The object of the invention is to provide 15 for the registration of each and every passenger who steps inside a car before he can alight therefrom.

Another object is to provide means by 20 which one turnstile only need be used in a double-end car, or a car designed to travel back and forth over a certain route, one end of the car being the forward end going but being the rear end returning.

A further object is to provide means so 25 that the passengers can not go from the entrance to the exit without passing through the turnstile.

A still further object is to provide means 30 by which the turnstile can be shifted from one side of the car to the other easily and expeditiously and then locked in its new position.

With these objects in view the invention 35 consists in certain novel features of construction, and in certain parts and combinations hereinafter to be described, and then more particularly pointed out in the claims.

Heretofore great trouble has been experienced in accurately registering the exact 40 number of passengers that step into and out of a car. But with the herein described invention no passengers can pass from the car until they have registered their presence in the car by a mechanical device appropriately situated, and which cannot be either tampered with or avoided. Nor will there 45 be any time lost in passing the passengers from entrance to exit; but if any should try to avoid paying fare the conductor can stop them from passing out of the car through 50 the exit; and the motorman can prevent them from alighting from the car from the door through which they entered.

In other inventions along these lines, one 55 turnstile has been used and the car must go

around a loop at the end of the route. But looping is often not practical in street railway work, and therefore double-end cars are more often used. This type of car heretofore needed two turnstiles, which is of course a disadvantage over using but one turnstile which the present invention accomplishes.

In the accompanying drawings:

Figure 1 is a plan view of the forward 65 part of a double-end car embodying the invention, showing a turnstile in position in full lines, and also showing the position in dotted lines of the same turnstile when the car is going in the opposite direction; the line M—N being the transverse center line of the car.

Fig. 2 is a transverse cross section of the 70 said car on the line A—B of Fig. 1, looking toward the front end of the car.

Referring now to these drawings, 1 represents the car, 2 the forward entrance thereto, 3 the motorman's seat, 4 the controller, 5 the drop-handle brake, 6 the air-brake, 7 the railings, 8 the passenger seats, 80 and 9 the exit; all of which are positioned as usual in the standard double-end car.

The invention itself is constructed and mounted substantially and preferably as follows: Along the transverse center line 85 M—N of the car, and on one side of the longitudinal center line of the same, the turnstile 10 is releasably mounted. The base 11 has wheels or rollers 12 attached thereto each wheel having a flange in the center 90 thereof and rolling in a grooved track 13 the said groove thereof registering with the flange of the said wheels. This track extends for about two-thirds the distance across the floor, or roof, of the car from 95 side to side thereof, and if laid on the floor of the car is flush with the same.

When the turnstile arrives at the end of its track, on one or the other of the sides of the car, bolts or fasteners 14 on the said base 100 fall by gravity into the holes 15 provided therefor, and adjacent to each end of the said track, and may be fastened therein in any convenient manner.

A change-board or counter, or shelf, 16, 105 behind which the conductor stands, is mounted above the turnstile and is releasably attached thereto, and runs on a separate track 17 similarly grooved to the track 13, the frame or legs 18 from the said change- 110

board projecting downwardly and ending in rollers 19 having a similar center flange to the said wheels or rollers 12.

A hand or foot lever 20 projects from the turnstile as usual, and from the outer end of the same a cord 21 runs over a pulley 22 attached to the top of the said change-board. The said rope then runs over the top of the change-board as at 23, then under a second pulley and ends in handle 24.

A second handle 25 is attached adjacent to the said first mentioned pulley 22, so that the operator can operate the said lever 20 if desired from either side of the change-board.

A stool 26 with legs or stand 27 and floor flange 28 fitting in a hole 29 in the floor of the car may be used by the operator if desired.

Vertical posts or poles or standards 30 rise from the floor of the car to the roof thereof, and are rigidly fastened to the top and the bottom of the same. Over these posts, by means of sleeves 31, slides the horizontal bar 32 in line with the longitudinal center line C—D of the car, the bar being prevented from dropping below the required height by the stops 33 which stops are provided with rubber cushions 34. When raised to its highest point as at 35, spring catches 36 in the said poles 30 prevent the bar from falling, and similar locks or catches hold the bar in its lower position.

Permanent partitions 36 rise from the floor to the ceiling of the car having open or wire-glazed panels 37 therein; and at the outer sides of two of these partitions are located slidable doors or partitions 38, sliding on countersunk tracks 39 which run across the floor to the said vertical posts. Locks 40 hold the doors 38 to one or the other of the said posts. The upper panels of these slidable doors register with the panels in the permanent partitions so that sight and ventilation are not interfered with to any appreciable extent.

The operation of the invention is essentially and preferably as follows: The car is traveling in the direction of the arrow 44, and therefore the passengers will board the car at the forward door or entrance 2, and will either decide to remain in the forward end of the car in the seats 8 and pay their fares when arriving at or near their destination, or they will pass through the turnstile into the rear part of the car where the seats may be unoccupied.

As one by one they pass into the narrow passageway 42 they pay their fare to the conductor seated or standing behind the change-board 16; or if a coin box be used they will at this place get the right change from the conductor. The passengers then walk one by one toward the turnstile and when the conductor pulls the cord 21, which

releases the mechanism of the turnstile, the passenger pushes his way through the same and may immediately go through the passageway 43 and out through the exit 9. Or he may pass through and beyond the 70 passage way 43 and occupy the seats in the rear end of the car, Fig. 1 showing but half of the car to the right of the transverse line M—N.

At the same time that the passenger passed 75 through the turnstile, the latter automatically registers his presence in the car and there is no way for the conductor to dispute this or derive any benefit from the fare of the passenger.

When the end of the route has been reached by the car, the conductor unfastens the bolts in the base of the turnstile, unlocks the forward partition from the horizontal bar, lifts up the latter till the spring 85 catches hold the same, and pulls over the turnstile and the change-board along their respective tracks to the dotted positions shown in Fig. 1. As soon as the turnstile and change-board arrives at the end of their 90 respective tracks the bolts in the base of the turnstile and the legs of the change-board automatically slip into their respective holes in the floor and are fastened therein. The conductor then slides the forward movable 95 partition back into its inoperative position. The horizontal bar is then brought down to its lower position and the opposite or rear movable partition is drawn toward the rear center pole and locked thereto. After the 100 conductor's seat has been placed in position, the car starts on its homeward journey and the conductor is ready to receive the fares of the passengers, who are now coming toward the turnstile from the reverse direction.

The invention is not limited in its use to double-end street railway cars only, but may be used in any other kind or type of car; or on any other kind of vehicle; and may be used on a non-moving platform if desired. Nor is the invention limited to any particular kind or type of turnstile.

It must be understood that various changes may be made in the form, proportion, size and detail of the several structures shown, as well as in the number and position of certain elements used, without departing from the spirit of the invention.

We claim:—

1. The combination with a turnstile, of a car holding the turnstile, and means permitting the turnstile to be moved from its normal operative position to a second operative position in the said car.
2. The combination with a turnstile, of a car holding the turnstile, and means permitting the turnstile to be moved from its normal operative position to a second operative position in the said car, and means

for clamping the turnstile in both its said operative positions.

3. The combination with a turnstile, of a car for holding the turnstile, and means 5 permitting the turnstile to be moved from its normal operative position on one side of the longitudinal center line of the said car to a second operative position on the other side of the said center line.

10 4. The combination with a turnstile, of a car for holding the turnstile, means permitting the turnstile to be moved from its normal operative position on one side of the longitudinal center line of the said car 15 to a second operative position on the other side of the said center line, and means for clamping the turnstile in both of its said operative positions.

5. The combination with a turnstile of a 20 car holding the turnstile, a track running transversely across the floor of the said car, wheels on the turnstile registering with the said track, and means permitting the turnstile to be moved from its normal operative 25 position on one side of the longitudinal center line of the said car to a second operative position on the other side of the said center line.

6. The combination with a turnstile, of a 30 car holding the turnstile, a track running transversely across the floor of the said car, wheels on the turnstile registering with the said track, means permitting the turnstile to be moved from its normal operative position 35 on one side of the longitudinal center line of the said car to a second operative position on the other side of the said center line, and means for clamping the turnstile in both its said operative positions.

40 7. The combination with a turnstile, of a car holding the turnstile, a track running transversely across the floor of the said car adjacent to the middle portion thereof, wheels on the turnstile registering with the 45 said track, and means permitting the turnstile to be moved from its normal operative position on one side of the longitudinal center line of the said car to a second operative position to the other side of the said center line.

50 8. The combination with a turnstile, of a car holding the turnstile, a track running across the floor of the said car adjacent to the middle portion of the said car, wheels 55 on the said turnstile registering with the said track, means permitting the turnstile to be moved from its normal operative position on one side of the longitudinal center line of the said car to a second operative 60 position on the other side of the said center line, and means for holding the turnstile rigidly to the floor of the said car in either of the said positions.

9. The combination with a turnstile, of a car, a track running transversely across 65 the said car over which the turnstile travels from one side of the car to the other, and a movable bar mounted between the two operative positions of the turnstile at either side of the said car. 70

10. The combination with a turnstile, of a car, a track running transversely across the said car over which the turnstile travels from one side of the car to the other, posts 75 running from floor to roof of the car and between which the turnstile must move when being changed from one side of the car to the other, a bar movably mounted on the said posts, and means for locking the said bar. 80

11. The combination with a turnstile, of a car, a track running transversely across the said car over which the turnstile travels from one side of the car to the other, a plurality of upright posts, and a bar movably 85 mounted on the said posts between the two operative positions of the turnstile at either side of the said car.

12. The combination with a turnstile, of a car, a track running transversely across 90 the said car over which the turnstile may travel from one side of the car to the other, a bar movably mounted between the two operative positions of the turnstile at either side of the said car, and means for locking 95 the said bar.

13. The combination with a turnstile, of a car, a track running transversely across the said car over which the turnstile may travel from one side of the car to the other, 100 a movable bar mounted between the two operative positions of the turnstile at either side of the said car, and means for locking the said bar in both its elevated and in its lower positions. 105

14. The combination with a turnstile, of a car, two transverse partitions in the said car mounted one on each side of the turnstile, means permitting the turnstile to be moved from its normal operative position 110 on one side of the longitudinal center line of the said car to a second operative position on the other side of the said center line, and means for locking the turnstile in each of its operative positions. 115

15. The combination with a turnstile, of a car, two uprights in line longitudinally to the said car, two transverse partitions mounted on one side of the said car each partition being opposite one of the said uprights, and a second and similar pair of transverse partitions mounted on the opposite side of the said car and also mounted opposite to the said uprights. 120
